RAILWAY BRAKING APPARATUS

Original Filed May 12, 1931

UNITED STATES PATENT OFFICE

HERBERT L. BONE, OF SWISSVALE, AND JOHN W. LIVINGSTON, OF WILKINSBURG, PENNSYLVANIA, ASSIGNORS TO THE UNION SWITCH & SIGNAL COMPANY, OF SWISSVALE, PENNSYLVANIA, A CORPORATION OF PENNSYLVANIA

RAILWAY BRAKING APPARATUS

Application filed May 12, 1931, Serial No. 536,750. Renewed May 4, 1932.

Our invention relates to railway braking apparatus, and particularly to braking apparatus of the type comprising a braking bar located in the trackway and actuated by a fluid pressure motor controlled from a remote point.

We will describe one form of railway braking apparatus embodying our invention, and will then point out the novel features thereof in the claims.

The accompanying drawing is a view, partly diagrammatic, illustrating one form of railway braking apparatus embodying our invention.

15 Referring to the drawing, the reference characters 1 and 1^a designate the track rails of a stretch of railway track. Located on opposite sides of rail 1, and extending parallel therewith, are two braking bars 2 and 3.

20 Two similar braking bars 2^a and 3^a extend parallel with rail 1^a on opposite sides thereof.

The braking bars 2, 3, 2^a and 3^a are operated by a fluid pressure motor M, which, in the form here shown, comprises a cylinder 25 4 containing an auxiliary piston 6 which is movable between the left-hand end of the cylinder and an intermediate point in the cylinder, and a main piston 5 which is movable between a retracted position at the right-hand end of the cylinder and a projected position where it engages the auxiliary piston 6. It will be plain, therefore, that when the auxiliary piston 6 occupies its projected position, in which position it is illustrated in the drawing, the stroke of the main piston 5 is less than when the auxiliary piston 6 occupies its retracted position. The sealing ring of the auxiliary piston 6 is located at 30 6^a in the drawing, and the parts are so proportioned that even when the auxiliary piston occupies its projected position, it does not blank a pipe 28 which communicates with the side of the cylinder 4. Piston 6 is provided with flutes or holes by means of which

40 the pipe 28 may at all times communicate with the region between pistons 5 and 6. The main piston 5 of motor M is attached to a piston rod 7, which piston rod, in turn, is operatively connected with the braking bars, 45 2, 3, 2^a and 3^a by means of suitable operating

mechanism, one form of which we will now describe.

As here shown, this operating mechanism comprises a link 8 which is connected at one end to the free end of the piston rod 7, and at the other end to one arm of a three-arm lever 9 which is pivotally supported in the trackway at 10. The second arm of the lever 9 is connected, through a link 11, with a crank 12 which is pivotally supported in the trackway at 13; and the third arm of lever 9 is connected, through a link 14, with a crank 15 which is pivotally supported in the trackway at 16. It will be seen, therefore, that the links 11 and 14 and the lever 9 constitute a toggle by means of which the cranks 12 and 15 may be swung in the same directions when the main piston 5 of motor M is operated. The free end of crank 12 is operatively connected with the braking bars 2 and 2^a, respectively, by means of resilient connections which include springs 17 and 18; and, similarly, the free end of the crank 15 is operatively connected with the braking bars 3 and 3^a by means of resilient connections which include springs 19 and 20. It will be seen, therefore, that when piston 5 moves toward the left, the cranks 12 and 15 are both swung in a clockwise direction, so that each braking bar is moved toward the associated rail into a braking position in which it engages the sides of a wheel of a railway car traversing the rails 1 and 1^a. When the piston 5 moves toward the right, however, the cranks 12 and 15 are both swung in counter-clockwise direction, and the braking bars are moved away from the associated rails to their non-braking positions, in which they are out of engagement with the wheels of a passing car. One form of operating mechanism of the type described is disclosed and claimed in a co-pending application for Letters Patent of the United States, Serial No. 307,895, filed by Herbert L. Bone on Sept. 24, 1928, for railway braking apparatus.

The motor M is controlled by four magnet valves V¹, V², V³ and V⁴. As here shown, each valve V comprises a valve stem 21, biased to an upper position by a spring 22, and provided with an armature 23 and a winding 24.

When valve V^1 is energized, valve stem 21 of this valve moves downwardly against the bias exerted by spring 22, as shown in the drawing, and a pipe 26, which communicates with the left hand end of cylinder 4, is then connected with a pipe 25 which is constantly supplied with fluid pressure, usually air, from a suitable source not shown in the drawing. When valve V^1 is deenergized, however, valve stem 21 is moved upwardly by spring 22, and pipe 26 is then disconnected from pipe 25. When valve V^2 is energized, valve stem 21 of this valve moves downwardly, thereby connecting pipe 26 with pipe 28, but when valve V^2 is deenergized, pipe 26 is disconnected from pipe 28. When valve V^3 is energized, a pipe 29 which communicates with right hand end of cylinder 4, is vented to atmosphere through a port 27; but when valve V^3 is deenergized, pipe 29 is disconnected from atmosphere, and pipe 28, which is disconnected from port 27 when this valve is energized, is then connected with port 27. When valve V^4 is energized, valve stem 21 of this valve moves downwardly and connects pipe 29 with pipe 25, but when valve V^4 is deenergized, pipe 29 is disconnected from pipe 25.

The valves V are controlled in part by a plurality of pressure responsive devices, each designated by the reference character P with a distinguishing exponent. Referring to the pressure responsive device P^{30} , for example, this device comprises a Bourdon tube 44 connected by means of a pipe 31 with pipe 28, and so subjected at all times to the pressure in the middle of cylinder 4. The Bourdon tube 44 controls a contact 45-45^a which is closed at all times except when the pressure exceeds a predetermined value which is just sufficient to move the braking apparatus to its open position. For example, this pressure might be thirty pounds per square inch. The pressure responsive devices P^{10} and P^{40} are similar to the pressure responsive device P^{30} , except that the Bourdon tubes 44 of these devices are connected to a pipe 30 which enters cylinder 4 at such point that these tubes will be subjected to the pressure in the region between the pistons 5 and 6 until piston 5 has moved toward the left just far enough to move the braking bars to their braking positions, after which these tubes will then be subjected to the pressure in the region between the main piston 5 and the right-hand end of the cylinder. That is to say, devices P^{10} and P^{40} are responsive to the pressure in front of piston 5 when the piston is in its retracted position, and to the pressure behind the piston when the latter is in its projected positions. The pressure responsive device P^{70} is likewise similar to the pressure responsive device P^{30} , but the Bourdon tube 44 of this latter device is connected with a pipe 32, which pipe in turn, is connected with the interior of cyl-

inder 4 at such point that this pipe will be blanked by piston 5 when and only when piston 5 occupies the position in which it engages the auxiliary piston 6 when the auxiliary piston 6 occupies its projected position. It will be seen, therefore, that when piston 5 occupies any position to the right of the position in which it engages the auxiliary piston 6 in the projected position of the latter, Bourdon tube 44 of pressure responsive device P^{70} will be subjected to the pressure in the region of cylinder 4 between the pistons 5 and 6; but that when the piston 5 occupies any position to the left of such position, the Bourdon tube 44 of the pressure responsive device P^{70} will then be subjected to the pressure in the region of cylinder 4 between the piston 5 and the right-hand end of the cylinder. The pressure responsive devices P^{10} , P^{40} and P^{70} are arranged to operate successively, as the pressure to which these devices are subjected is increased. For example, for all pressures below ten pounds per square inch, contact 45-45^a of each of these devices is closed. If the pressure exceeds ten pounds per square inch, however, contact 45-45^a of device P^{10} opens, and if the pressure exceeds twenty pounds per square inch, contact 45-45^b of device P^{10} closes. In similar manner, the pressure responsive devices P^{40} and P^{70} are adjusted to open their contacts 45-45^a at forty and seventy pounds per square inch, respectively, and to close their contacts 45-45^b at fifty and eighty pounds per square inch. Of course, these specific pressures are not essential, but are only mentioned for purposes of explanation.

The valves V are further controlled by means of a manually operable lever L which, as here shown, is capable of assuming five positions, indicated by the dotted lines in the drawing, and designated by the reference characters p^0 , p^1 , p^2 , p^3 and p^4 . The lever L controls a plurality of contacts 33-34, 35-36, 37-38, 39-40, 41-42, 43-46 and 43-47. Contacts 33-34 and 43-46 are closed when lever L occupies its p^0 position; contact 35-36 is closed when lever L occupies its p^1 position; contact 37-38 is closed when lever L occupies its p^2 position; contact 39-40 is closed when lever L occupies its p^3 position, its p^4 position, or any position intermediate these two; contact 41-42 is closed when lever L occupies its p^1 position, its p^3 position, or any position between these two positions; and contact 43-47 is closed when lever L occupies its p^4 position.

The lever L will usually be located at a point remote from the braking apparatus, as in the control cabin of a classification yard car retarder system, and will be connected with the braking apparatus by means of line wires extending from the control cabin to the braking apparatus.

As shown in the drawing, lever L occupies its p^0 or "off" position. A circuit is therefore completed for valve V^3 at contact 33—34 of lever L, and current flows from a suitable source, here shown as a battery B, through line wire 48, winding 24 of valve V^3 , wires 49 and 50, asymmetric unit 51 in its low resistance direction, line wire 52, wire 53, contact 33—34 of lever L, and wires 54, 55, 56 and 57 back to battery B. Valve V^3 is therefore energized, so that the right-hand end of cylinder 4 is connected with atmosphere at port 27. With lever L in its p^0 position, a circuit is also completed for valve V^2 at contact 43—46 of lever L, and current flows from battery B through line wire 48, winding 24 of valve V^2 , line wire 58, contact 43—46 of lever L, and wire 57 back to battery B. Valve V^2 is therefore also energized, so that pipe 26 is connected with pipe 28. Furthermore, with lever L in its p^0 position, if the pressure in the region of cylinder 4 between the pistons 5 and 6 is below thirty pounds per square inch, a circuit will also be completed for valve V^1 , which passes from battery B through line wire 48, winding 24 of valve V^1 , wire 59, contact 45—45^a of pressure responsive device P^{30} , line wire 52, wire 53, contact 33—34 of lever L, and wires 54, 55, 56 and 57 back to battery B. Valve V^1 will therefore become energized and will connect pipe 26 with pipe 25. When pipe 26 becomes connected with pipe 25 under these conditions, fluid pressure will be admitted to the left-hand end of the cylinder, and also to the region between the pistons 5 and 6, until the pressure in these regions exceeds thirty pounds per square inch, at which time contact 45—45^a of pressure responsive device P^{30} will open and will de-energize valve V^1 . Valve V^4 is deenergized. It will be seen, therefore, that when lever L occupies its p^0 position, piston 5 of motor M is held in its extreme right-hand position in cylinder 4 by a pressure of thirty pounds per square inch, and the braking bars therefore occupy their retracted or ineffective positions. Since piston 5 occupies its extreme right-hand position, the Bourdon tubes 44 of the pressure responsive devices P^{10} , P^{40} and P^{70} are subjected to the pressure in the region of cylinder 4 between the pistons 5 and 6. Contact 45—45^b of device P^{10} , contact 45—45^a of device P^{40} , and contact 45—45^a of device P^{70} are therefore all closed, while contact 45—45^a of device P^{10} , contact 45—45^b of device P^{40} and contact 45—45^b of device P^{70} are all open.

In explaining the operation of the apparatus as a whole, I will first assume that the operator wishes to make a comparatively light brake application. To do this, he moves lever L to its p^1 position, thereby opening contacts 33—34 and 43—46 of lever L and closing contacts 35—36 and 41—42 of lever

L. The opening of contact 33—34 interrupts the circuit previously traced for valve V^3 , and the opening of contact 43—46 opens the circuit previously traced for valve V^2 , so that valves V^3 and V^2 now become deenergized. The deenergization of valve V^3 disconnects pipe 29 from atmosphere, and connects pipe 28 with atmosphere, while the deenergization of valve V^2 disconnects pipe 26 from pipe 28, thus disconnecting the region between the pistons 5 and 6 from the left-hand end of cylinder 4. The openings of contact 33—34 of lever L also interrupts the circuit previously traced for valve V^1 . It should be noted that when pipe 28 becomes connected with atmosphere, the pressure in this region of cylinder 4 between pistons 5 and 6 rapidly decreases to atmosphere pressure, so that if contact 45—45^a of pressure responsive device P^{30} happens to be open when lever L is moved to its p^1 position, this contact will almost immediately become closed. Furthermore, due to the decreased pressure in the region between the pistons 5 and 6, contact 45—45^b of pressure responsive device P^{10} , which was previously closed, will become open, and contact 45—45^a which was previously open, will become closed. As soon as contacts 41—42 of lever L and contact 45—45^b of pressure responsive device P^{30} both become closed, a circuit is completed for valve V^1 which passes from battery C through wire 61, contact 41—42 of lever L, wire 60, line wire 52, contact 45—45^a of pressure responsive device P^{30} , winding 24 of valve V^1 , and line wire 48 back to battery C. Valve V^1 therefore becomes energized, and admits fluid at full line pressure to the left-hand end of the cylinder to hold the auxiliary piston 6 in its projected position under these conditions. Furthermore, as soon as contact 45—45^a of pressure responsive device P^{10} and contact 35—36 of lever L both become closed, a circuit is completed for valve V^4 which passes from battery C through wires 61 and 62, contact 35—36 of lever L, wire 63, line wire 64, asymmetric unit 65 in its low resistance direction, wire 66, contact 45—45^a of pressure responsive device P^{10} , wires 67 and 68, winding 24 of valve V^4 , and line wire 48 back to battery C. Valve V^4 therefore becomes energized and connects pipe 29 with pipe 25, so that fluid pressure is now supplied to the right-hand end of the cylinder. This pressure drives piston 5 toward the left, thereby moving the braking bars toward their braking positions. It should be noted that the pressure available to commence the movement of the braking bars may be built up to full line pressure which may be of the order of one hundred pounds per square inch, so that the response of the apparatus is very rapid. When the main piston 5 has moved to the left far enough so that the braking bars are in such positions that they will engage the wheels of a car in

the braking apparatus, Bourdon tubes 44 of the pressure responsive devices P^{10} and P^{40} become subjected to the pressure in the right hand end of the cylinder. Inasmuch as this pressure under these conditions is full line pressure, the contacts 45-45^a of these devices now become opened and the contacts 45-45^b become closed. The opening of contact 45-45^a of pressure responsive device P^{10} 5 interrupts the circuit previously traced for valve V^4 , and valve V^4 therefore now becomes deenergized, thereby cutting off the supply of fluid pressure to the right-hand end of cylinder 4. The closing of contact 45-45^b 10 of pressure responsive device P^{10} completes a circuit for valve V^3 , and current flows from battery C through wires 61 and 62, contact 35-36 of lever L, wire 63, line wire 64, asymmetric unit 65 in its low resistance direction, wire 66, contact 45-45^b 15 of pressure responsive device P^{10} , wire 49, winding 24 of valve V^3 , and line wire 48 back to battery C. Valve V^3 therefore becomes energized and connects pipe 29 with port 27 so that the right-hand 20 end of cylinder 4 is then exhausted to atmosphere. This end of the cylinder will then continue to be exhausted to atmosphere until the pressure therein has been reduced below twenty pounds per square inch, whereupon contact 45-45^b 25 of pressure responsive device P^{10} will open and will deenergize valve V^3 . If the pressure in the right-hand end of cylinder 4 now decreases below ten pounds per square inch for any reason, contact 45-45^a 30 of pressure responsive device P^{10} will again become closed and will complete the circuit previously traced for valve V^4 including this contact, so that valve V^4 will again become energized. Valve V^4 will then remain energized until the pressure in the right-hand end 35 of the cylinder exceeds ten pounds per square inch at which time contact 45-45^a of pressure responsive device P^{10} will again open to deenergize this valve. It will be apparent, 40 therefore, from the foregoing, that when lever L occupies its p^1 position, piston 5 is urged toward the left by a pressure of between ten and twenty pounds per square inch. The movement of piston 5 toward the left 45 under these conditions is limited by the auxiliary piston 6, which as pointed out hereinbefore, is held in its projected position by fluid at full line pressure, and the parts are so proportioned that the movement of lever 50 9 caused by this movement of piston 5 does not bring the toggle of which lever 9 forms a part, to its dead-center position. It follows, therefore, that when a car enters the 55 braking apparatus, the braking bars may be forced away from the rails, thereby transmitting the reaction of the wheels through the operating mechanism to the piston 5. As a result, the piston 5 may be moved slightly 60 to the right, thereby cushioning the braking 65

action of the apparatus against the volume of air in cylinder 4.

If the operator desires to make a more powerful application, he will move lever L to its p^2 position, in which position contacts 37-38 and 41-42 are closed. The operation of the apparatus is then similar to that just described with the following exceptions. Valve V^4 is now initially energized over a circuit which includes contact 37-38 of lever 70 L, and which passes from battery B through line wire 48, winding 24 of valve V^4 , wire 68, contact 45-45^a of pressure responsive device P^{40} , wire 69, asymmetric unit 70 in its low 75 resistance direction, line wire 64, wire 71, contact 37-38 of lever L, and wires 55, 56 and 57 back to battery C. When piston 5 has moved toward the left to the position in which devices P^{10} and P^{40} become subjected to the pressure in the right-hand end of the 80 cylinder, contact 45-45^a of pressure responsive device P^{40} will open and contact 45-45^b thereof will become closed. The opening of contact 45-45^a of this pressure responsive device will interrupt the circuit last traced 85 for valve V^4 and so will deenergize this valve. The closing of contact 45-45^b of device P^{40} under these conditions, will complete another circuit for valve V^3 , and current will flow from battery B through line wire 48, winding 24 of valve V^3 , wires 49 and 72, contact 45-45^b of device P^{40} , wire 69, asymmetric unit 70 in its low resistance direction, line 90 wire 64, wire 71, contact 37-38 of lever L, and wires 55, 56 and 57 back to battery B. Valve V^3 will therefore become deenergized and will vent fluid from the right-hand end 95 of cylinder 4 until the pressure in this end of the cylinder decreases below fifty pounds per square inch. If the pressure in this end 100 of the cylinder under these conditions decreases below forty pounds per square inch for any reason, contact 45-45^a of pressure responsive device P^{40} will again become closed and will energize valve V^4 to supply fluid pressure to this end of the cylinder until the pressure again exceeds forty pounds per square 105 inch. It will be apparent, therefore that when lever L occupies its p^2 position, the piston 5 is forced toward the left-hand end of cylinder 110 4, and is held against auxiliary piston 6, by fluid under a pressure of between forty and fifty pounds per square inch.

If the operator moves lever L to its p^3 position, a circuit is completed for valve V^4 from 115 battery B through line wire 48, winding 24 of valve V^4 , wires 68 and 73, contact 45-45^a of pressure responsive device P^{70} , line wire 74, contact 39-40 of lever L, and wires 56 and 57 back to battery B. Valve V^4 therefore 120 becomes energized and admits fluid pressure to the right-hand end of cylinder 4 to move piston 5 toward the right in the manner previously described. Under these conditions piston 6 is held in its projected position by 125 130

virtue of the circuit previously traced for valve V^1 , including contact 41-42 of lever L, so that the movement of piston 5 is arrested when it engages the auxiliary piston 6. As previously pointed out when piston 5 occupies the position in which it engages the auxiliary piston 6 it blanks the pipe 32 by means of which the Bourdon tube 44 of pressure responsive device P^{70} communicates with cylinder 4, and it will be apparent, therefore, that under these conditions contact 45-45^a of pressure responsive device P^{70} remains closed so that valve V^4 remains energized. Piston 5 is therefore held in the position in which it engages the auxiliary piston 6 by fluid at full line pressure.

If it is desirable to apply a still higher braking force, the operator moves lever L to its p^4 position, thereby opening contact 41-42 and closing contact 43-47. When contact 41-42 is opened, the circuit previously traced for valve V^1 including this contact is interrupted and valve V^1 therefore becomes deenergized, so that the supply of fluid pressure to the left-hand end of cylinder 4 is cut off. When contact 46-47 of lever L becomes closed, a circuit is completed for valve V^2 which is similar to the circuit previously traced for this valve except that this circuit instead of including the contact 43-46 of lever L includes contact 43-47 of lever L. Valve V^2 therefore becomes energized, and since all circuits for valve V^3 are now open, so that valve V^3 is deenergized, the left-hand end of cylinder 4 is vented to atmosphere. Furthermore, since contact 39-40 of lever L is closed under these conditions, the circuit last traced for valve V^4 is closed, and valve V^4 therefore also becomes energized. Fluid at full line pressure is therefore admitted to the right-hand end of cylinder 4 in the manner previously described, and since the left-hand end of cylinder 4 is vented to atmosphere, this pressure moves the pistons 5 and 6 to the extreme left-hand end of the cylinder. As soon as piston 5 moves past the position in which it engages the auxiliary piston 6 in its projected position, pressure responsive device P^{70} becomes subjected to the pressure in the right-hand end of the cylinder. Inasmuch as this pressure is full line pressure, contact 45-45^a of device P^{70} now becomes opened and contact 45-45^b becomes closed. The opening of contact 45-45^a interrupts the circuit last traced for valve V^4 so that this valve becomes deenergized, while the closing of contact 45-45^b of pressure responsive device P^{70} completes another circuit for valve V^3 which passes from battery B through line wire 48, winding 24 of valve V^3 , wires 49 and 72, contact 45-45^b of pressure responsive device P^{70} , line wire 74, contact 39-40 of lever L, and wires 56 and 57 back to battery B. Valve V^3 therefore becomes energized and vents fluid from the right-hand end of cylinder 4

until the pressure in this end of the cylinder decreases below eighty pounds per square inch. It will be apparent, therefore, that under these conditions, piston 5 is held in its extreme left hand position by a pressure of between seventy and eighty pounds per square inch. The parts are so proportioned that when piston 5 occupies this position, lever 9 occupies the position in which the toggle of which it forms a part is nearly on dead-center. When the parts occupy these positions, the reaction of ordinary car wheels is not sufficient to move the toggle mechanism and the entire forces exerted by the springs 17, 18, 19 and 20 of the resilient connections are available to hold the braking bars against the wheels of a car. If, however, when the parts occupy these positions, a locomotive should enter the braking apparatus, the additional force exerted on the braking bars by the wide driving wheels of the locomotive will be sufficient to move the toggle mechanism away from its dead-center position thus relieving the strain on the apparatus and hence preventing damage to the braking apparatus under these latter conditions.

It should be observed that if the operator moves the lever L from a position corresponding to a higher braking force to a position corresponding to a lower braking force, the apparatus will immediately and automatically reduce the braking force to a value corresponding to the new position of the lever, for reasons which will be apparent from the drawing without tracing the operations in detail.

In order to restore the apparatus from its closed or effective position to its open or ineffective position, the operator moves lever L to its p^0 position in which it is illustrated in the drawing. The closing of contact 33-34 of lever L under these conditions completes the circuit previously traced for valves V^1 and V^3 , while the closing of contact 43-46 completes the circuit previously traced for valve V^2 . Valves V^1 , V^2 and V^3 therefore now all become energized. The energization of valve V^1 admits fluid pressure to the left-hand end of cylinder 4 so that the auxiliary piston 6 is moved to its projected position in which it is illustrated in the drawing. The energization of valve V^2 connects pipe 26 with pipe 28, and since valve V^1 is energized so that pipe 26 is supplied with fluid pressure, fluid pressure is then admitted to the region between the pistons 5 and 6. The energization of valve V^3 disconnects pipe 28 from atmosphere and connects pipe 29 with atmosphere. When pipe 29 is connected with atmosphere, the pressure in the right-hand end of cylinder 4 is exhausted, and the pressure between the pistons 5 and 6 therefore moves piston 5 toward the right to restore the braking apparatus to its open or ineffective position in which it is illus-

trated in the drawing. If the pressure in the region of cylinder 4 between the pistons 5 and 6 exceeds thirty pounds per square inch during the movement of piston 5 toward the right, contact 45-45^a of pressure responsive device P³⁰ will open as previously described and will interrupt the circuit for valve V¹ including this contact. Valve V¹ will, therefore, become deenergized and cut off the supply of fluid pressure to the region between the auxiliary piston 6 and the adjacent end of the cylinder, and between the pistons 5 and 6. After the pressure has again dropped below thirty pounds per square inch, contact 45-45^a of pressure responsive device P³⁰ will again become closed to restore the circuit for valve V¹. It will be seen, therefore, that piston 5 is moved to its right-hand position and is subsequently maintained in this position by a pressure of thirty pounds per square inch. When the piston reaches its right-hand position, the parts are restored to their normal conditions in which they are illustrated in the drawing.

25 Although we have herein shown and described only one form of railway braking apparatus embodying our invention, it is understood that various changes and modifications may be made therein within the scope of the appended claims without departing from the spirit and scope of our invention.

Having thus described our invention, what we claim is:

1. Trackway car retarding apparatus comprising a cylinder, a piston movable therein and having a retracted and a projected position, means for normally admitting fluid pressure in front of said piston to move it to its retracted position, means for at times admitting fluid pressure behind said piston to move it to its projected position, pressure responsive means connected with said cylinder at such point as to be subjected to the pressure in front of said piston when the piston is in its retracted position and to the pressure behind the piston when the piston is in its projected position, means controlled by said pressure responsive means for determining the pressure behind said piston, and car retarding means operated by said piston.

2. Trackway car retarding apparatus comprising a cylinder, a piston movable therein and having a retracted and a projected position, means for at times moving said piston to its retracted position, means for at other times admitting fluid pressure behind said piston to move it to its projected position, pressure responsive means connected with said cylinder at such point as to become subjected to the pressure behind said piston when and only when said piston has been moved away from its retracted position more than a predetermined distance, means controlled by said pressure responsive means for

controlling the pressure behind said piston, and car retarding means operated by said piston.

3. Trackway car retarding apparatus comprising a cylinder, a piston movable therein and having a retracted and a projected position, means for at times moving said piston to its retracted position, means for at other times admitting fluid pressure behind said piston to move it to its projected position, pressure responsive means connected with said cylinder at such point as to become subjected to the pressure behind said piston when and only when said piston has been moved away from its retracted position more than a predetermined distance, means controlled by said pressure responsive means and effective when said pressure means becomes subjected to the pressure behind the piston for decreasing this pressure a predetermined amount, and car retarding means operated by said piston.

4. Trackway car retarding apparatus comprising a cylinder, a piston movable therein and having a retracted and a projected position, means for at times moving said piston to its retracted position, means for at other times admitting fluid pressure behind said piston to move it to its projected position, pressure responsive means connected with said cylinder at such point as to become subjected to the pressure behind said piston when and only when said piston has been moved away from its retracted position more than a predetermined distance, means controlled by said pressure responsive means and effective when said pressure means becomes subjected to the pressure behind the piston for decreasing this pressure to, and for subsequently maintaining it at, a value which falls within predetermined limits, and car retarding means operated by said piston.

5. Trackway car retarding apparatus comprising a cylinder, a piston movable therein and having a retracted and a projected position, means for at times moving said piston to its retracted position, two magnet valves, means controlled by the one valve for admitting fluid pressure behind said piston to move it to its projected position, means controlled by the other valve for exhausting fluid pressure from behind said piston, pressure responsive means connected with said cylinder at such point as to be subjected to the pressure behind said piston when and only when said piston has been moved away from its retracted position more than a predetermined distance, means controlled by said pressure responsive means for controlling said two magnet valves, and car retarding means operated by said piston.

6. Trackway car retarding apparatus comprising a cylinder, a piston movable therein and having a retracted and a projected position, means for at times moving said piston

to its retracted position, two magnet valves, means controlled by the one valve for admitting fluid pressure behind said piston to move it to its projected position, means controlled by the other valve for exhausting fluid pressure from behind said piston, a pressure responsive device connected with said cylinder at such point as to be subjected to the pressure behind said piston when and only when said piston has been moved away from its retracted position more than a predetermined distance, a normally closed contact controlled by said pressure responsive device and arranged to become opened if the pressure to which said pressure responsive device is subjected exceeds a predetermined value, a normally open contact controlled by said pressure responsive device and arranged to become closed if the pressure to which said pressure responsive device is subjected exceeds a predetermined value which is somewhat higher than the value at which said normally closed contact becomes opened, a circuit for said one valve controlled by said normally closed contact, a circuit for said other valve controlled by said normally open contact, and car retarding means controlled by said piston.

7. Trackway car retarding apparatus comprising a cylinder, a piston movable therein and having a retracted and a projected position, a first magnet valve effective when energized for admitting fluid pressure in front of said piston to move it to its retracted position, a second magnet valve effective when energized for admitting fluid pressure behind said piston to move it to its projected position, a third magnet valve for exhausting fluid pressure from in front of said piston or behind said piston according as said third valve is deenergized or energized, a pressure responsive device connected with said cylinder at such point as to be subjected to the pressure in front of said piston when the piston is in its retracted position and to the pressure behind the piston when the piston has been moved away from its retracted position more than a predetermined distance, a normally closed contact controlled by said pressure responsive device and arranged to become opened if the pressure to which said pressure responsive device is subjected exceeds a predetermined value, a normally open contact controlled by said pressure responsive device and arranged to become closed if the pressure to which said pressure responsive device is subjected exceeds a predetermined value which is somewhat higher than the value at which said normally closed contact becomes opened, means for at times energizing said first magnet valve, means including said normally closed contact for at other times energizing said second magnet valve, means including said normally open contact for at still other times

energizing said third magnet valve, and car retarding means controlled by said piston.

8. Trackway car retarding apparatus comprising a cylinder, a piston movable therein and having a retracted and a projected position, means for at times moving said piston to its retracted position, means for at other times admitting fluid pressure behind said piston to move it to its projected position, a plurality of pressure responsive devices each responsive to a different pressure and connected with said cylinder at spaced points along the cylinder so positioned that when said piston occupies its retracted position none of said devices will be subjected to the pressure behind said piston but that as said piston is moved from its retracted position toward its projected position said devices will become subjected to the pressure behind said piston in the order of their response to increasing pressures, means for controlling the pressure of the fluid admitted to said cylinder behind said piston by a selected one of said devices, and car retarding means controlled by said piston.

In testimony whereof we affix our signatures.

HERBERT L. BONE.
JOHN W. LIVINGSTON.
